COUNTER ASSEMBLAGE

Mark M. Hennessy, Milwaukee, Wis., assignor to
 Durant Manufacturing Co., Milwaukee, Wis., a
 corporation of Wisconsin

Application November 20, 1939, Serial No. 305,310

12 Claims. (Cl. 235—132)

The present invention relates generally to improvements in the art of registering, and relates more specifically to improvements in the construction and operation of counter assemblies which are adapted to perform certain operations when the indicating elements have moved a predetermined distance.

Generally defined, an object of my present invention is to provide an improved counter assembly which is adapted to quickly and effectively trip or release mechanisms of various types for action, whenever the counter wheels have moved into a predetermined position; and which may be quickly and accurately pre-set to produce any desired subsequent operation or registration.

In certain industries such as oil well drilling, it frequently becomes desirable to perform some operation such as inserting a plug or perforating a casing, at some definite depth within a conduit. For such purposes, it is desirable to utilize a carriage or member of some kind which may be readily advanced along the interior of the conduit, in conjunction with a registering device such as a counter for positively stopping the travel of the carriage when the predetermined location has been reached by the carriage. In order to quickly stop the travelling member when advancing at relatively high speed along the well casing, considerable power may be required; but the counter mechanism which is necessarily rather frail and sensitive, should not be subjected to undue stress when the powerful stop mechanism is set for action preparatory to stopping and locking the travelling carriage. The counter, in an assembly of this type, should be thoroughly protected against damage; should also be adapted for rapid and convenient pre-setting, should moreover be readily removable for inspection and replacement from its housing casing; and should furthermore be prevented from rotating reversely when its carrying element is withdrawn from the well casing. So far as known, none of the prior counter assemblies have been well adapted for such varied service, nor have they met all requirements imposed by such usage; and the previous counting devices have therefore been unsatisfactory for depth measuring and well plugging or similar purposes.

It is therefore a more specific object of my invention to provide an improved counter assembly which is adapted to quickly and effectively trip relatively heavily loaded power mechanisms, and wherein the delicate counting mech-

anism is not stressed or interfered with due to loading of the power mechanism.

Another specific object of this invention is to provide an improved trip mechanism operable by a counter having a series of numeral wheels, and which will permit convenient pre-setting of the counter wheels so as to insure operation of the trip mechanism when any predetermined or definite count has been effected.

A further specific object of the invention is to provide an improved counter mechanism for actuating a trip lever or the like when the counter is rotated in one direction, and in which the counter will not be affected by rotation of its driving elements in the opposite direction.

Still another specific object of my present invention is to provide an improved subtraction counter assembly which may be pre-set to perform a definite function when all of the numeral wheels thereof reach zero position, and which can be manufactured at moderate cost.

An additional specific object of my invention is to provide an improved protective housing for a counter and trip assembly, and means for effecting convenient insertion and removal of the counter with respect to the housing.

Another additional object of this invention is to provide a simple, compact and durable multiple wheel counter and trip mechanism which may be utilized for diverse purposes, and the various parts of which may be readily constructed and assembled to provide a most efficient counter unit.

These and other specific objects and advantages of my present invention will be apparent from the following detailed description, and the present improved counter is especially applicable to conduit measuring and well plugging assemblies such as shown and described in my co-pending application, Serial No. 303,085, filed November 6, 1939.

A clear conception of the several features constituting my present improvement, and of the construction and operation of counters built in accordance with the invention, may be had by referring to the drawing accompanying and forming a part of this specification wherein like reference characters designate the same or similar parts in the various views.

Fig. 1 is a side elevation of one of my improved counter assemblies housed within a tubular casing (in section) and showing the latch mechanism set in solid lines, and released in dot-and-dash lines;

Fig. 2 is a transverse section through the coun-

50
 55

ter and latch assembly of Fig. 1, taken along the line 2—2 and showing the latch mechanism released;

Fig. 3 is a similar transverse section through the assembly of Fig. 1, also taken along the line 2—2 but showing the latch mechanism set;

Fig. 4 is another transverse section through the counter and latch assembly of Fig. 1, taken along the line 4—4 and showing the manner in which the counter may be removed from the tubular housing;

Fig. 5 is still another transverse section through the assembly of Fig. 1, taken along the line 5—5 and showing the counter wheel retaining hook in active position in solid lines, and in released position in dot-and-dash lines;

Fig. 6 is an enlarged central longitudinal section through portions of several of the counter numeral wheels;

Fig. 7 is a similarly enlarged transverse section through the counter of Fig. 6, taken along the line 7—7; and

Fig. 8 is a likewise enlarged transverse section through the counter of Fig. 7, taken along the line 8—8.

While I have specifically shown and described my invention as being applied to subtraction counter of the multiple numeral wheel type cooperating with a trip mechanism especially adapted for use in well plugging devices, it is not the intent to unnecessarily restrict the scope or utility of the improvement by virtue of such specific embodiment of the improved features.

Referring to the drawing, the improved counter and trip mechanism assemblage shown therein, comprises in general, a counter wheel supporting frame having separated end members or heads 10 rigidly interconnected by parallel rods 11, 12 and having shafts 13, 14 journaled therein and disposed parallel to the rods 11, 12; a series of six similar numeral wheels 15 of successively higher order proceeding away from the unit wheel 15', rotatably supported upon and slidable along the rotary shaft 13, and each having a cam or hub section 16 provided with a peripheral notch 17; a series of five mutilated pinions 18 rotatably mounted upon the fixed rod 11 and drivingly interconnecting the adjacent numeral wheels 15; bevel gearing 19 for imparting rotation to the counter wheel supporting shaft 13; a disk 20 rigidly attached to the shaft 13 and carrying a spring pressed pawl 21 which coacts with a ratchet wheel 22 rigidly attached to the unit counter wheel 15' to impart rotation from the shaft 13 to the wheel 15' in one direction only; a series of six trip pawls 23 swingably suspended from the fixed rod 12 and each having a rounded end projection 24 cooperable with one of the notches 17, and also having a hook 25 and an abutment 26; a tension spring 27 connecting a pin 28 on each pawl 23 with the shaft 14, and tending to force the corresponding pawl projection 24 into snug engagement with the periphery of the adjacent cam section 16; a tubular casing or housing 29 with the interior of which the frame heads 10 are snugly cooperable, and having a side opening normally closed by a removable cover 30, but through which the counter assembly is insertible or removable; a curved pawl release lever 31 secured to the shaft 14 and swingable about the shaft axis by a relatively strong tension spring 32 so as to cause projecting plates 33 carried by the shaft 14 to engage the pawl abutments 26 and lift the pawls 23 away from the cam sections 16 when

the cover 30 is removed; a latch lever 34 swingably suspended within the housing 29 by a pivot pin 35 coacting with a bracket 36 and having a latch retaining and release cam 37; a rod 38 slidable by means of a fluid pressure actuated bellows 39 in a partition 40 disposed within the housing 29, and having an abutment collar 41 cooperable with a hook lever 42 with which the cam 37 is in turn cooperable; and an axially movable work performing rod 43 which is slidable longitudinally within the tubular housing 29 by means of fluid under pressure within the bellows 39 acting upon the intervening rod 38 and cross-head 44, when the hook lever 42 is withdrawn from the collar 41.

As shown in Figs. 2, 3 and 5, the end members or heads 10 of the counter frame are formed to normally snugly engage the interior of the tubular housing 29 while providing proper clearances for the rod 43 and for the movable latch lever 34; and the frame heads 10 are normally secured within the housing 29 by thumb screws 45 which also serve to hold the cover 30 in place. Upon removal of the cover 30 as in Fig. 4, the fastenings for the frame heads 10 are also released, and the entire counter assemblage may then be swung in a clockwise direction from normal position as in Fig. 2 about the central axis of the housing 29, until the uppermost edges of the end walls 10 clear the right hand edge 30 of the housing opening. The counter assemblage may thereafter be withdrawn as a unit, laterally away from the housing axis as shown in Fig. 4, and removed through the side opening in the tubular housing 29. Reinsertion of the counter assemblage may be just as readily effected by reversing the procedure; and it is to be noted that when the cover 30 is removed, the pawl release lever 31 will be swung by the spring 32 through the housing opening to the position shown in Fig. 4, thereby causing the projections 33 to engage all of the pawls 23 and to swing these pawls away from the peripheries of the hub sections 16 of all counter wheels 15. Removal of the closure cover also permits inspection and setting of the counter, and movement of the trip lever 34 into latching engagement with the pawl hooks 25; and the lever 34 will be retained in latched position whenever any one or more of the numeral wheels 15 is out of zero position, whereas release of all hooks 25 will cause the lever 34 to trip.

As previously indicated, the improved counter comprises a series of six numeral wheels 15 of progressively higher order proceeding away from the unit numeral wheel 15', and all of the numeral wheels 15 are of simplified and similar or interchangeable construction except that the unit wheel 15' has the ratchet wheel 22 secured thereto. All of the numeral wheels 15 are freely rotatable about and are slidable along the driving shaft 13, and the hub sections 16 are not drivingly connected to this shaft by keys or splines. Besides the hub section 16, each numeral wheel 15 has a transfer disk or washer 46 and a rider disk or lock washer 47 on one side of its notched rim; and also has a numeral section 48, a plain spacing washer 49, an enlarged groove forming plate 50, and a driving or transfer gear 51 on the opposite side of its notched rim; all of these elements being rigidly united by rivets 52, see Figs. 6, 7 and 8. The numeral section 48 of each numeral wheel 15 has a series of equally spaced numerals 53 ranging from zero to nine, which are definitely spaced with respect to the 75

notch 17 of the corresponding wheel; and the sections 48 cooperate with the adjacent disks or plates 49, 50 to form peripheral grooves 54, see Fig. 6. The mutilated transfer pinions 18 which 5 drivingly interconnect the adjoining numeral wheels 15, are rotatably and slidably supported upon the fixed rod 11, and each of these pinions 18 has a disk 55 and an adjacent annular groove 56 coacting with the groove 54 and large plate 10 50 of an adjacent numeral wheel 15, in the manner illustrated in Fig. 6. Each pinion 18 has eight teeth of which the four teeth 57 extend entirely across the pinion and are adapted to 15 coact not only with the adjacent teeth of the transfer washer 46 and gear 51, but also with a notch 58 in the adjacent lock washer 47; while the teeth 59 are shorter and do not engage the notch 58 at any time. The assemblage is obviously such, that it requires one complete revolution 20 of each numeral wheel 15 of lower order, to cause one-tenth of a revolution of the adjacent numeral wheel 15 of next higher order; and the numerals 53 may be arranged to either subtract from or add to the total indication made by the 25 counter. As shown, the successive units, tens, etc., are subtracted from any predetermined total to which the counter has been set, and the trip lever 34 is released when zero position of indication has been reached by all numeral wheels 15.

In order to permit pre-setting or re-setting of the counter numeral wheels 15, it is necessary to cause each pinion 18 to disengage at least one of the two adjacent numeral wheels 15, by relatively shifting the wheels 15, and their pinions 30 along the shaft 13 and rod 11. Each of the pinions 18 by virtue of the coaction of its disk 55 with the plate 50 of the adjacent wheel 15, is laterally shiftable with that wheel, and while the adjacent wheels 15 and pinions 18 are normally 35 disposed as shown in Fig. 6, I have provided simple but effective means for releasing the wheels and their pinions, this means comprising a hook 60 swingably suspended from one of the frame heads 10 by a pivot pin 61 as illustrated in Fig. 5. The hook 60 is adapted to be positioned as shown in solid lines in Fig. 5, in order to prevent axial displacement of the wheels 15 and pinions 18 when the counter is in operating condition; but the hook 60 may be swung outwardly through the 40 housing opening when the cover 30 is removed, as shown in dot-and-dash lines, so as to permit free shifting and separation of the numeral wheels 15 and pinions 18, sufficient to permit setting of the wheels 15. When the numeral wheels 45 55 and their pinions have been separated sufficiently to cause the long pinion teeth 57 to disengage the teeth of the transfer disk 46, the numeral wheels 15 may be rotated freely for pre-setting; but when the series of wheels 15 and pinions 18 60 have been brought back to proper position as in Fig. 6, and the hook 60 has been restored at the end of the numeral wheel of highest order, the wheels 15 cannot separate, and the cover 30 will then prevent displacement of the hook 60 sufficiently to permit separation of the counter wheels. 65 The counter wheels 15, pinions 18, driving ratchet, latch pawls 23, and hook 60 are all carried by and are transferable with the frame heads 10, as a unitary structure, and the driving gears 19 70 may be rotated from any desired source of propulsion.

While I have shown a specific type of power mechanism with which the trip lever 34 coacts when the counter wheels 15 reach a predetermined position, this mechanism is merely illus-

trative and constitutes no specific part of my present invention. The fluid pressure actuated bellows 39 which normally exerts considerable pressure against and axially of the rod 38, may be replaced by a compression spring or the like; and while this power or pressure is exerted through the abutment 41 against the latch lever 42 and cam 31, it does not affect the lever 34 and latch pawls 23, and therefore does not interfere with the normal operation of the counter assemblage. 10 When the trip mechanism is actuated, the bellows 39 causes the rod 43 to move longitudinally with considerable force, and this motion can be utilized to perform useful work of any desired kind. The counter trip mechanism may be set 15 or released manually upon removal of the cover 30, and the lever 34 will automatically retain the lever 34 in set position when the cover 30 is removed so that the power mechanism will not be released for action during setting of the counter. 20

During normal operation of my improved counter and trip mechanism, the parts are ordinarily disposed as shown in Fig. 1, with the trip lever 34 engaged by one or more of the pawls 23 and with the projections 24 of the lever engaging pawls 23 riding on the circular periphery of the hub section 16 of the corresponding numeral wheel or wheels 15. As the gearing 19 is rotated in one direction, the shaft 13 and disk 20 will be rotated, thereby causing the pawl 21 to rotate 30 the unit numeral wheel 15' through the ratchet wheel 22. Reverse rotation of the gearing 19 and shaft 13, will not however impart rotation to the unit wheel 15'. The rotation of the wheel 15' causes the numeral wheels 15 of higher order, 35 to rotate intermittently by correspondingly shorter steps, or at correspondingly slower speeds, until all of the notches 17 of the several wheels 15 reach a position of alignment parallel to the shaft 13. When this position is reached, all of 40 the wheels 15 will be in zero indicating position, and the projections 24 of all of the trip pawls 23 will then be forced into the adjacent notches 17 by the springs 27 thereby releasing the trip lever 34. It will therefore be noted that if the initial 45 setting of the counter wheels 15 is for say one thousand, seven hundred and fifty units or operations, this number will be reduced by one unit or operation for each one-tenth of a revolution of the unit number wheel 15', and the trip lever 50 34 will be completely released from all trip pawls 23 when the total number of units or operations has been completed.

In order to again pre-set the counter and the trip mechanism after completion of the count 55 and release of the latter, it is only necessary to remove the cover 30, whereupon the bent lever 31 will automatically raise all of the trip pawls 23 out of engagement with the numeral wheel hub sections 16. The hook 60 may then be 60 swung clear of the counter numeral wheels 15, after which these wheels may be separated and freely rotated to the desired positions. After the wheels 15 have been properly set and restored to normal driving position, the hook 60 may be returned to proximity with the shaft 13, thereby 65 completing the counter resetting operation, and it is to be noted that the hook 60 cannot be thus restored to retaining position unless all of the pinions 18 have been returned to proper driving engagement with the adjacent transfer disks 46 and notches 58. When the numeral wheels 15 have been properly set and locked in position, the trip lever 34 may be returned to set position in 70 engagement with the pawl hooks 23. The cover 75

30 may then be applied to the housing opening and fastened in place thereby completing the pre-setting operation, and returning the release lever 31 to released position within the counter housing.

5 From the foregoing detailed description it will be apparent that my present invention provides an improved counter assemblage which is extremely simple and compact in construction, and 10 which is adapted to quickly and effectively trip relatively heavily loaded power mechanisms without subjecting the counting mechanism to undue stress or strain during normal operation thereof. The improved counter assemblage embodies relatively simple numeral wheels which can be readily manufactured and assembled and which may 15 be conveniently pre-set to insure operation of the trip mechanism when a predetermined number of units have been counted or operations have 20 been performed. While the counter wheels may be rotated in one direction, the improved ratchet mechanism will prevent rotation thereof in the opposite direction due to reversal of the rotation of the initial driving mechanism. The subtraction 25 counter assemblage may be conveniently pre-set to the predetermined number of operations which are to be performed, and the trip mechanism will be actuated when all wheels reach zero position, and the assemblage is especially adapted to be inserted 30 within and confined in a tubular housing of relatively small diameter. The counter assemblage may obviously be used for diverse purposes and may be manufactured and sold at moderate cost.

35 It should be understood that it is not desired to limit this invention to the exact details of construction or to the precise mode of use, herein shown and described, for various modifications within the scope of the claims may occur to 40 persons skilled in the art.

I claim:

1. In a counter assemblage, a series of numeral wheels rotatable about a common axis and each having a numeral bearing rim and a peripheral notch, motion transfer means interconnecting the adjacent numeral wheels, a trip pawl cooperable with said notch of each of said wheels, a trip lever swingable about an axis disposed transversely of said series axis and being engageable by said trip pawls when said pawls are out of engagement with said notches, and power mechanism movable parallel to said series axis and being operable to move said trip lever when all of said pawls engage all of said wheel notches, 55 said wheels being substantially relieved of pressure exerted by said mechanism at all times.

2. In a counter assemblage, a series of numeral wheels rotatable about a common axis and each having a numeral bearing rim and a peripheral notch, motion transfer pinions interconnecting the adjacent numeral wheels, a trip pawl cooperable with said notch of each of said wheels, each of said pawls being spring pressed toward the adjacent wheel and having a hook portion, a trip lever swingable about an axis disposed transversely of said common axis and being engageable with said hook portions of said trip pawls, and power mechanism movable parallel to said common axis and being operable to swing said trip lever when all of said hook portions are released by engagement of said pawls with said wheel notches, said wheels being substantially relieved of pressure exerted by said mechanism at all times.

75 3. In a counter assemblage, a series of nu-

meral wheels rotatable about a common axis and each having a numeral bearing rim and a peripheral notch, motion transfer means interconnecting the adjacent numeral wheels, a trip pawl cooperable with said notch of each of said wheels, 5 a trip lever fulcrumed beyond an end of said series to swing about an axis transverse to said common axis and being cooperable with all of said trip pawls, power mechanism having a member movable parallel to said common axis and 10 operable to swing said trip lever about said transverse axis when all of said pawls engage all of said wheel notches, and common means for positively moving all of said pawls away from the adjacent wheels and into engaging position relative 15 to said trip lever.

4. In a counter assemblage, a series of numeral wheels rotatable about a common axis and each having a numeral bearing rim and a peripheral notch, means for transferring motion from 20 each of said wheels to the adjacent wheel, a trip pawl spring pressed toward said notch of each of said wheels, a trip lever fulcrumed to swing about a transverse axis remote from said wheel series and having a portion extending parallel to said 25 common axis engageable by said pawls, power mechanism movable parallel to said common axis and operable to swing said trip lever when said 30 wheels reach a predetermined position relative to the cooperating pawls, and a spring urged lever for positively moving all of said pawls out of engagement with the adjacent wheels and toward trip lever engaging position.

5. In a counter assemblage, a tubular housing having side opening, a frame insertible through 35 said opening and being disposable in snug coaction with the interior of said housing, a series of numeral wheels rotatably supported solely by said frame, means for transferring motion from each of said wheels to an adjacent wheel, a trip pawl 40 coacting with the periphery of each of said wheels, and a trip lever swingably suspended within said housing independently of said frame and being engageable by all of said pawls.

6. In a counter assemblage, a tubular housing 45 having an opening, a frame mounted within said housing adjacent said opening, a series of numeral wheels rotatably supported by said frame and each having a peripheral notch, a trip pawl cooperable with said notch of each of said wheels, 50 common means for moving all of said pawls out of engagement with said wheels, and a closure for said housing opening cooperating with said common moving means to render the same ineffective when said closure is effective to close said opening.

7. In a counter assemblage, a tubular housing having a side opening, a frame insertible through said opening and being mountable in said housing adjacent said opening, a series of numeral 60 wheels rotatably supported by said frame and each having a notch therein, a trip pawl cooperable with said notch of each of said wheels, common means for moving all of said pawls out of 65 said notches, and a cover for said opening cooperating with said common means to render said pawls ineffective when said cover is in place.

8. In a counter assemblage, a circular tubular housing having a side opening, a frame having segmental circular end elements insertible 70 through said opening and rotatable after insertion into snug coaction with the circular interior of said housing, a series of numeral wheels supported solely by said frame, a cover for closing said opening, and means for securing said cover 75

to said housing and for locking said frame against rotation.

9. In a counter assemblage, a housing having an opening, a frame mounted within said housing, a series of numeral wheels rotatably journaled in said frame, a trip pawl cooperable with each of said wheels, common means for rendering all of said pawls ineffective, and a cover for said opening cooperable with said means to actuate the same when said cover is in place.

10. In a counter assemblage, a series of numeral wheels rotatable about a common axis and each having a peripheral notch, a trip pawl cooperable with the notch of each of said wheels, a trip lever swingable about another axis disposed transversely of said common axis and being cooperable with all of said trip pawls when the latter are out of engagement with said notches, and a power device movable parallel to said common axis and being operable to swing said trip lever away from said series when all of said pawls engage all of said notches.

11. In a counter assemblage, a series of numeral wheels rotatable about a common axis and each having a peripheral notch, a trip pawl cooperable with the notch of each of said wheels, a trip lever swingable about another axis disposed transversely of said common axis and being co-

operable with all of said trip pawls when the latter are out of engagement with said notches, a power device movable parallel to said common axis and being operable to swing said trip lever away from said series when all of said pawls engage all of said notches, and a latch lever interposed between said power device and said trip lever for substantially relieving the latter from pressure exerted by the former.

12. In a counter assemblage, a tubular housing having an opening, a frame insertible within and removable from said housing through said opening, a series of numeral wheels journaled in said frame for rotation about a common axis parallel to the housing axis and each having a peripheral notch, a trip pawl cooperable with the notch of each of said wheels, a trip lever swingably mounted in said housing independently of said frame and about another axis disposed transversely of said common axis and being cooperable with all of said trip pawls when the latter are out of engagement with said notches, and a power device within said housing and movable therewith to swing said trip lever away from said wheels when all of said pawls engage all of said notches.

MARK M. HENNESSY.
